COMBINED LOADER AND CAB

Bruce L. Renquist, Racine, Wis., assignor to J. I. Case
Company, Racine, Wis., a corporation of Wisconsin

Filed Aug. 11, 1967, Ser. No. 8,233

Term of patent 14 years

(Cl. D14—3)

FIG. 1 is a side elevational view of my new design for a combined loader and cab. The side opposite is the same as the side shown.

FIG. 2 is a front elevational view of FIG. 1.

FIG. 3 is a rear elevational view of FIG. 1.

FIG. 4 is a top plan view of FIG. 1.

I claim:

The ornamental design for combined loader and cab, substantially as shown.
